UNITED STATES PATENT OFFICE.

LAURENCE E. TOPHAM, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

BOBBIN-WINDING MACHINE.

Application filed April 30, 1918, Serial No. 231,611. Renewed November 20, 1925.

This invention relates to winding machines, and more particularly to winding machines for winding sewing machine bobbins.

5 The primary object of the invention is to produce a bobbin winding machine upon which filled bobbins having a portion of the thread wound on the bobbin in one direction and the remainder of the thread wound on 10 the bobbin in the reverse direction may be produced in a rapid, efficient and reliable manner.

With this object in view, the machine is provided with driving connections for driving 15 the winding shaft in reverse directions, and a feature of the invention contemplates the provision of automatically acting means for actuating and controlling the driving connections to drive the winding shaft in 20 one direction during the winding of the first part of the bobbin and to drive the winding shaft in the reverse direction during the winding of the remainder of the bobbin.

In the preferred form of the invention, 25 the direction of rotation of the winding shaft is reversed when the winding shaft has executed a predetermined and definite number of rotations at the beginning of the winding operation, or when a predetermined 30 length of thread has been wound on the bobbin. In the present embodiment of the invention the shifting of the driving connections to reverse the direction of rotation of the winding shaft is controlled by a 35 mechanism which is driven in definite relation to the winding shaft during the rotation of the winding shaft in the first direction at the beginning of the winding operation. This mechanism registers the rotation 40 of the winding shaft in the first direction and times the action of the mechanism for shifting the driving connections or determines the point in the rotation of the shaft at which the direction of rotation of 45 the shaft is reversed. When the winding shaft has described a predetermined number of rotations in the first direction, or when a predetermined number of coils or turns of 50 thread have been wound on the bobbin, this mechanism causes the automatic shifting of the driving connections to reverse the direction of rotation of the winding shaft.

Other objects of the invention are to improve the construction and mode of operation 55 of bobbin winding machines, and with

this object in view the invention comprises certain other novel and improved features hereinafter described and particularly pointed out in the claims.

The features of the invention will be readily understood from the accompanying drawings illustrating the invention in its preferred form, and the following detailed description of the constructions therein shown.

In the drawings, Figure 1 is a plan view of a bobbin winding machine embodying the invention; Fig. 2 is a view in front elevation, partly in section, of the machine; Fig. 3 is a view, partly in plan and partly in horizontal section, of a portion of the machine, illustrating certain of the parts in different positions from the positions in which they are shown in Fig. 1; Fig. 4 is a plan view, partly in section, of the machine, illustrating certain of the parts in still different positions from the positions in which they are shown in Figs. 1 and 3; Fig. 5 is a view, 70 in side elevation, partly in section, of the machine; Fig. 6 is a detail sectional view, 75 taken substantially on the line 6—6 of Fig. 3; Fig. 7 is a detail view in side elevation illustrating particularly certain parts of the mechanism for clamping a bobbin on the bobbin winding shaft; Fig. 8 is a perspective view illustrating certain parts of the mechanism for clamping a bobbin on the bobbin winding shaft; Fig. 9 is a view similar to Fig. 8, illustrating the parts in different relative positions; Fig. 10 is a view 80 similar to Figs. 8 and 9, illustrating the parts in still different relative positions; Fig. 11 is a transverse sectional view and Fig. 12 is a view in side elevation, showing a partially wound bobbin at an early stage 85 in the winding operation; Fig. 13 is a transverse sectional view and Fig. 14 is a view in side elevation, showing a partially wound bobbin at a later stage in the winding operation; Fig. 15 is a transverse sectional view 90 with a portion of the thread broken away; and Fig. 16 is a view in side elevation of a completely wound bobbin.

The machine illustrated in the drawings 105 comprises a rotatable and longitudinally movable bobbin-carrying winding shaft 2 mounted in suitable bearings and having a reduced left-hand end portion indicated at 4 upon which a bobbin may be secured as shown in Figs. 1, 2 and 4, the bobbin being 110

indicated at B in these figures. The shaft 2 is mounted to slide longitudinally in a bearing in a sleeve 6 journaled in a bearing in the upright 8 on the frame and is mounted 5 to rotate and slide longitudinally in a bearing in a bushing 10 clamped in the upright 12 on the frame. The sleeve 6 is secured to rotate with the winding shaft by means of a key 14 mounted on the shaft and engaging 10 in a longitudinal groove in the sleeve. Journaled side by side upon the winding shaft between the bearings for the shaft are two driving pulleys 16 and 18, which are driven in opposite directions as indicated by 15 the arrows in Fig. 1, by means of driving belts 20 and 22. Clutch devices are provided for connecting the pulley 16 and the pulley 18 alternatively with the winding shaft. These clutch devices comprise a disk 24 secured 20 to the winding shaft, and a clutch pin 26 secured in the disk with its ends projecting laterally from the disk, a clutch pin 28 mounted in the driving pulley 16 and arranged to engage the left-hand end of the 25 clutch pin 26, and a clutch pin 30 mounted in the driving pulley 18 and arranged to engage the right-hand end of the clutch pin 26.

When the machine is idle the winding 30 shaft is held in the longitudinal position shown in Fig. 2 with the clutch pin 26 located in central position between the clutch pins 28 and 30 so that its respective ends clear said clutch pins, the driving pulleys 16 35 and 18 then rotating idly on the shaft. To connect the winding shaft with the driving pulley 16, the shaft is shifted longitudinally to the left to carry the left-hand end of the clutch pin into the path of the clutch pin 28, as shown in Fig. 3, and in a corresponding manner to connect the winding shaft with the driving pulley 18 the shaft is shifted longitudinally to the right to carry the right-hand end of the clutch pin 26 into the 40 path of the clutch pin 30, as shown in Fig. 4. Upon starting the machine the winding shaft is shifted to the left to clutch the same to the driving pulley 16. The shaft is driven by the driving pulley 16 in the direction indicated by the arrow in Fig. 3 until a predetermined number of turns or coils of thread have been wound on the bobbin and the shaft is then automatically shifted to the 45 right to unclutch the shaft from the driving pulley 16 and to clutch the same to the driving pulley 18. The shaft is then driven by the driving pulley 18 in the opposite direction or in the direction indicated by the arrow in Fig. 4 until the winding of a bobbin is completed. Upon the completion of the winding of a bobbin the shaft is shifted to the left to its idle position to unclutch the shaft from the driving pulley 18 and cause 50 the shaft to come to rest.

The longitudinal position of the winding

shaft is controlled by a bell crank shifting lever 32 pivoted at 34 on the frame and having a fork formed at the end of its vertically extending arm, the members of which embrace a sleeve 33 secured on the winding 70 shaft by a nut 38 threaded on the end of the shaft, said members engaging between flanges 40 formed on the sleeve. To the end of the horizontally extending arm of the bell crank shifting lever 32 is pivotally connected the upper end of a rod 42 mounted in a sleeve 44. A coiled spring 46 surrounds the rod within the sleeve, and is interposed between collars 48 and 50 mounted on the rod. The collar 48 is arranged to engage an abutment 52 formed on the rod 42 and the inwardly projecting end wall of the sleeve, while the collar 50 is arranged to engage a collar 54 mounted on the lower end of the rod and an abutment 56 formed on the interior of the sleeve. With this construction relative longitudinal movement of the sleeve and rod in either direction will compress the coiled spring 46. The lower end of the sleeve 44 is connected to the upper end of a treadle rod 58, the lower end of which is pivotally connected with a treadle shown conventionally in Fig. 5, and indicated by reference numeral 60. The treadle 60 is pivoted at 62 and is acted upon by a coiled spring 64, the strength of which is considerably greater than that of the coiled spring 46 so that the former spring will lift the treadle and treadle rod against the action of the latter spring. The upward movement of the treadle 95 and treadle rod is limited by a stop pin 66 arranged to engage the treadle. With this construction the elevation of the treadle rod upon the release of the treadle tends through the spring 46 to swing the bell 100 crank shifting lever 32 in a direction to shift the winding shaft to the left to clutch the pulley 16 to the shaft, and the depression of the treadle rod tends through said spring to swing the shifting lever 32 in a direction to 105 shift the winding shaft to the right to clutch the pulley 18 to the shaft.

The movement of the shifting lever 32 is controlled by a latch lever 68 pivoted on a stud 70 and having a laterally extending arm upon which is formed a projection 72 arranged to engage a projection 74 formed on a plate secured to one of the members of the fork on the vertically extending arm of the shifting lever. The latch lever is acted upon by a coiled spring 72 which tends to swing the lever in a direction to carry the laterally extending arm thereof forwardly. The latch lever is also formed with a forwardly extending arm terminating in a handle 76.

The parts are so constructed and arranged that with the projection 72 on the latch lever located at the left of projection 74 on the shifting lever and in contact therewith, as shown in Fig. 1, the longitudi- 130

nal position of the winding shaft as determined by the shifting lever is such that the shaft is unclutched from both driving pulleys, and with the projection 72 located at 5 the right of the projection 74 and in contact therewith, as shown in Fig. 3, the longitudinal position of the winding shaft is such that the shaft is clutched to the pulley 16. Figs. 1 and 2 show the positions of the parts 10 when the machine is idle, the projection 72 on the latch lever being located to the left of the projection 74 on the shifting lever and the treadle being released. The shifting lever is held in position with the 15 projection 74 in contact with the projection 72 so that the shaft is unclutched from both pulleys by the action of the treadle spring 64 and the intermediate spring 46. The sleeve 44 is held in elevated position 20 by the treadle spring, thereby placing the spring 46 under considerable compression (see Fig. 2).

With the parts in the positions shown in 25 Figs. 1 and 2, after a bobbin has been secured in place on the end of the winding shaft, the operator starts the machine by grasping the handle of the latch lever and swinging the same to the right. The swinging movement of the latch lever thus produced 30 disengages the projection 72 on the latch lever from the projection 74 on the shifting lever, allowing the latter lever to be actuated by the coiled spring 46 to shift the winding shaft longitudinally to the left 35 to clutch the shaft to the pulley 16. Upon the release of the operating handle on the latch lever, said lever is swung back to its original position by the action of the coiled spring 76, thereby locating the projection 40 72 on the lever to the right of the projection 74 on the shifting lever, as shown in Fig. 3. After this occurs the operator depresses the treadle. During the depression of the treadle the shifting lever is held 45 from swinging movement by the engagement of the projection 72 with the projection 74, and the coiled spring 46 is compressed by the downward movement of the sleeve 44. The treadle is held down by the 50 operator until the winding of a bobbin is completed. When a predetermined number of coils or turns have been wound on the bobbin, the latch lever is automatically actuated to disengage the projection 72 55 from the projection 74. The coiled spring 46 then actuates the shifting lever to shift the winding shaft longitudinally to the right to unclutch the shaft from the driving pulley 16 and to clutch the same to the 60 driving pulley 18. The rotation of the winding shaft is thus automatically reversed and the thread is thereafter wound upon the bobbin in the reverse direction. The winding shaft is held in position longitudinally with the driving pulley 18

clutched thereto by the depression of the treadle until the operator releases the treadle upon the completion of the winding of the bobbin. After the winding shaft is shifted to the right the latch lever is again 70 swung back to its original position by the coiled spring 76, thereby locating the projection 72 in position at the left of the projection 74. Obviously, in shifting the winding shaft to the right far enough to clutch 75 the shaft to the driving pulley 18, the shifting lever is actuated to carry the projection 74 to the right somewhat beyond the projection 72, as shown in Fig. 4. Upon the release of the treadle and the elevation 80 of the treadle rod under the action of the treadle spring 64 at the completion of the winding of a bobbin, the shifting lever is actuated during the first part of the upward movement of the treadle to shift the 85 winding shaft to the left to unclutch the shaft from the driving pulley 18, the movement of the shifting lever being stopped by the engagement of the projection 74 with the projection 72. During the further upward movement of the treadle rod the sleeve 44 moves upwardly independently of the rod, thereby compressing the coiled spring 46, as shown in Fig. 2. The parts 90 are thus restored to their original idle positions.

The mechanism for automatically actuating the latch lever to disengage the projection 72 from the projection 74 and thereby cause the shifting of the winding shaft to 100 reverse the direction of rotation thereof after a predetermined number of turns have been wound on the bobbin comprises a longitudinally movable and rotatable shaft 78 mounted at one end in a bearing supported 105 in the upright 8 and at the other end in a bearing supported in an arm 80 on the upright. The shaft 78 is driven from the winding shaft 2 through a gear 82 secured to one end of the sleeve 6 and a gear 84 secured to 110 a sleeve 86 journaled in a bearing in the upright 8, the sleeve 86 forming a bearing for the left-hand end of the shaft 78. During the rotation of the winding shaft, the gear 84 is driven through the sleeve 6 and gear 82 115 from the winding shaft in a direction depending on the direction of rotation of the winding shaft and at a speed depending on the ratio of the sizes of the gears. These gears are preferably proportioned so that 120 the speed of rotation of the gear 84 is considerably less than that of the winding shaft. The shaft 78 is driven from the gear 84 in a definite relation to the winding shaft during the rotation of the winding shaft in 125 the direction of the arrow, Fig. 3, or during the winding of the predetermined length of thread on the bobbin through a suitable clutch which is inactive during the rotation of the winding shaft in the direction of the 130

arrow, Fig. 4, or during the winding of the remainder of the bobbin. The rotation of the winding shaft in the direction of the arrow, Fig. 3, drives the gear 84 in the direction of the arrows, Figs. 5 and 6, while the rotation of the winding shaft in the direction of the arrow, Fig. 4, obviously will drive the gear 84 in a direction reverse to that of the arrows, Figs. 5 and 6. The shaft 78 is driven from the gear 84 through a dog clutch comprising a clutch dog 88 pivoted at 90 on the gear and a sleeve 92 mounted on the shaft 78 to rotate with the shaft, and having a notch in its periphery which forms an abutment 94 arranged to be engaged by the projection 96 on the clutch dog. The clutch dog is acted upon by a coiled spring 98 which tends to maintain the projection 96 on the clutch dog in the notch in the sleeve but allows the clutch dog to swing outwardly to disengage the projection from the notch. The sleeve 92 is connected with the shaft 78 by means of a pin 100 mounted in the shaft with its outer end engaging in a longitudinal groove in the sleeve, which connects the sleeve for rotation with the shaft and allows the shaft to move longitudinally through the sleeve. The projection 96 in the clutch dog and the abutment 94 in the sleeve are so constructed and arranged that during the rotation of the gear 84 in the direction of the arrows, Figs. 5 and 6, the gear is clutched to the sleeve 92 by the clutch dog and drives the sleeve and shaft 78, while during the rotation of the gear in the reverse direction the clutch dog is inactive, allowing the gear to rotate independently of the sleeve. The arrow on Fig. 3 indicates the direction of rotation of the shaft 78 when the shaft is driven from the gear 84 through the clutch dog 88. The sleeve is acted upon by a coiled spring 102 interposed between the outer end of the sleeve and the hub of a disk 104 secured to the shaft, which maintains the inner end of the sleeve in frictional engagement with the gear 84 to cause the gear to drive the sleeve and the shaft 78 during the rotation of the gear in a direction reverse to the arrows, Figs. 5 and 6. As shown clearly in Fig. 3, the right-hand end of the shaft 78 is formed with a series of screw threads indicated at 106 and is threaded into a nut formed in a sleeve 108 secured by a clamp in the outer end of the arm 80. Through the engagement of the end of the shaft 78 in the sleeve 108, longitudinal movement will be imparted to the shaft by the rotation of the shaft. The threads upon the shaft and sleeve are what are ordinarily known as left-hand threads, so that as the shaft is driven in the direction of the arrow, Fig. 3, by the rotation of the gear 84, the shaft will be moved longitudinally to the left.

65 The shaft 78 by its longitudinal movement to the left thus registers the rotations of the winding shaft during the first part of the winding operation. The point in the winding operation at which the latch lever is actuated to disengage the projection 72 from the projection 74 to cause the shifting of the winding shaft to reverse the direction of rotation of the shaft is timed by the longitudinal movement of the shaft 78 so that the direction of rotation of the winding shaft is reversed after the winding shaft has executed a predetermined number of rotations at the beginning of the winding operation. To this end, the disk 104 carries an inclined projection 110 which at a certain point in the longitudinal movement of the shaft 78 is adapted to engage a contact stud 112 mounted on a rearwardly extending arm on the latch lever. By the engagement of the projection 110 with the contact stud 112 the latch lever is swung in a direction to disengage the projection 72 on the lever from the projection 74 on the shifting lever 32. The longitudinal position of the shaft 78 at the start of the winding of a bobbin is determined by an abutment screw 115 threaded into the outer end of the sleeve 108 and arranged to engage the end of the shaft 78, as shown in Fig. 3. Figs. 1 and 3 illustrate clearly the position of the shaft 78 at the start of the winding of a bobbin, Fig. 1 showing the positions of the parts before the latch lever has been actuated to start the machine, and Fig. 3 showing the positions of the parts just after the winding shaft has been shifted to clutch the shaft to the driving pulley 16. It will be noted that at the start of the winding operation of the projection 110 on the disk 104 is located some distance from the contact stud 112 on the latch lever. Upon starting the machine, as the winding shaft is clutched to the driving pulley 16 and is driven in the direction indicated by the arrow in Fig. 3, by said pulley, through the driving connections between the winding shaft and the shaft 78 the latter shaft is driven at relatively slow speed in the direction of the arrow in said figure. The rotary movement of the shaft 78 in this direction causes the shaft to move longitudinally to the left. After the winding shaft has described a predetermined number of rotations, or after a predetermined number of turns of thread have been wound on the bobbin, the projection 110 on the disk 104 engages the contact stud 112 and actuates the latch lever to disengage the projection 72 on the lever from the projection 74 on the shifting lever 32. When this occurs, as above stated, the shifting lever is actuated by the action of the coiled spring 46 to shift the winding shaft longitudinally to clutch the shaft to the driving pulley 18. As the gear 84 upon the reversal in the direction of rotation of the winding shaft is rotated in a

direction reverse to the arrows, Figs. 5 and 6, the sleeve 92 is rotated in the same direction through the frictional engagement of the inner end of the sleeve with the gear, the coiled spring 102 then being under comparatively heavy compression, as shown in Fig. 4, so that the inner end of the sleeve is held with considerable pressure against the gear. By the rotary movement 5 thus imparted to the sleeve 92 the shaft 78 is rotated in the direction of the arrow, Fig. 4, and is moved longitudinally to the right to its original position. The number of rotations executed by the winding shaft before 10 the latch lever is actuated by the engagement of the projection 110 with the contact stud 112 to cause the reversal in the direction of rotation of the winding shaft, or the time in the rotation of the shaft during the first part 15 of the winding operation at which the direction of rotation of the shaft is reversed depends upon the position of the disk 104 at the start of the winding operation, which is determined by the initial longitudinal position 20 of the shaft 78. The initial longitudinal position of the shaft may be adjusted to regulate, as desired, the number of rotations executed by the winding shaft before its direction of rotation is reversed by an adjustment 25 of the abutment screw 115. Should the operator fail to have depressed the treadle when the latch lever is actuated to disengage the projection 72 from its position at the right of the projection 74 by the engagement 30 of the projection 110 with the stud 112, the shifting lever 32 is then actuated by the movement of the latch lever to shift the winding shaft to the right into its idle position, as shown in Fig. 2. To this end an 35 abutment screw 113 is mounted on the forwardly extending arm of the latch lever, and one of the members of the fork on the shifting lever is formed with a lateral extension, indicated at 114 in the drawings, adapted to 40 engage the abutment screw 113. The winding shaft may then be shifted to the right from its idle position to clutch the same to the pulley 18 by the depression of the treadle. 45 The machine is provided with improved 50 devices for clamping a bobbin upon the bobbin winding shaft which will enable the bobbin quickly and easily to be clamped upon the winding shaft upon starting the machine, and to be unclamped from the winding shaft when the winding of the bobbin has been completed. The clamping devices for the bobbin comprise a flange 116 55 formed on the winding shaft and arranged to engage one side of the bobbin, and a clamping member 118 arranged to engage 60 the other side of the bobbin. The clamping member 118 is mounted upon the inner end of a rod 120 having a cylindrical enlargement or head 122 engaging in a cylindrical 65 recess in the clamping member. The rod

120 is mounted for longitudinal and rotary movement in a sleeve 124 and is formed at its outer end with a series of right-hand screw threads engaging corresponding screw threads formed in the sleeve. The sleeve 70 124 is mounted for longitudinal and rotary movement in an arm 126 pivoted at 128 on the frame, and carries a milled hand wheel 130. As shown clearly in Figs. 3, 8, 9 and 10, the end of the winding shaft is slabbed 75 off upon its opposite sides, as indicated at 132, and is cut away at 134, thereby forming lateral projections 136. The cylindrical head 122 on the end of the rod 120 is provided with a longitudinal slot 138 to receive the end of the winding shaft, with recesses 140 to receive the lateral projections 136 on the shaft, and with projections 142 to engage the lateral projections on the shaft. With the end of the winding shaft 80 and the head of the rod 120 in the relative positions shown in Fig. 8, by moving the rod longitudinally toward the shaft, the end of the shaft is engaged in the slot 138, as shown in Fig. 9. With the parts in the 85 positions shown in the latter figure, upon turning the winding shaft in the direction of the arrow, the lateral projections 136 on the shaft are engaged in the recesses 140, or are located behind the projections 142 on 90 the head of the rod. These relative movements are imparted to the rod and winding shaft in clamping a bobbin on the shaft. 95 Before a bobbin is placed on the end of the winding shaft the sleeve 124, rod 120 100 and clamping devices 118 are swung rearwardly into the positions shown in full lines in Fig. 7, out of line with the winding shaft so that the end of the winding shaft is unobstructed. After a bobbin has been placed 105 on the end of the winding shaft, the sleeve, rod and clamping device are swung back into axial alignment with the winding shaft, as shown in dotted lines in Fig. 7. The sleeve 124 is then forced longitudinally 110 to the right by the operator until the head 122 of the rod 120 engages the end of the winding shaft, and is then rotated until the end of the winding shaft engages in the slot 140, as shown in Fig. 9. With the parts 115 in the relative positions shown in this figure, the operator, while holding the hand wheel 130, starts the machine by an actuation of the latch lever 68. As the winding shaft starts to rotate, the rod 120 remains stationary and the lateral projections 136 on the shaft are engaged in the recesses 140 in the head of the rod behind the projections 142. Upon the engagement of the lateral projections on the shaft with the end faces of the 120 recesses, rotary movement is imparted to the rod 120 by the rotation of the winding shaft. The rotation of the rod 120, while the sleeve 124 is held from rotation, will 125 produce a relative longitudinal movement of 130

the rod and the sleeve 124 in a direction to draw the head of the rod toward the inner end of the sleeve. During the relative longitudinal movement of the sleeve and rod 5 the projections 142 on the head of the rod are drawn firmly against the projections 136 on the winding shaft, and the inner end of the sleeve is engaged with the clamping member 118 and forces the clamping member firmly against the outer side of the bobbin. When the bobbin is securely clamped 10 between the flange 116 and the clamping member 118, the operator releases the hand wheel 130, allowing the sleeve 124 to rotate 15 freely in the arm 126 during the remainder of the winding operation. At the completion of the winding of a bobbin, the winding shaft is rotating in the direction of the arrow, Fig. 4, and in unclamping the bobbin 20 from the bobbin winding shaft, the operator, while the shaft is still running, grasps the hand wheel 130, thereby arresting the rotation of the sleeve 124. Through the continued rotation of the rod 120 a relative 25 longitudinal movement of the rod and sleeve will occur in a direction to project the head of the rod from the inner end of the sleeve. This relative movement of the sleeve and rod will relieve the clamping member 118 30 from clamping engagement with the outer side of the bobbin, and will relieve the pressure of the projections 142 against the lateral projections 136, allowing the winding shaft to turn relatively to the head 122 of 35 the rod into the position shown in Fig. 9. In removing the bobbin from the winding shaft, the rod 120 is moved longitudinally to the left by a longitudinal movement of the sleeve 124, and the sleeve, rod and 40 clamping devices are then swung into the positions shown in full lines in Fig. 7 to permit the removal of the bobbin.

The forward movement of the arm 126 is limited by the engagement of a projection 45 144 on the arm with an adjustable abutment screw 146. This abutment screw is adjusted so that when the arm 126 is swung into position to engage the projection 144 with said screw, the sleeve 124, rod 50 120, and clamping device 118 will be located accurately in axial alignment with the winding shaft. To hold the arm 126 either in the position shown in dotted lines in Fig. 7, or in the position shown in full lines in said figure, the arm is engaged by 55 the free end of a leaf spring 148 secured by a screw 150 to the frame. This spring is arranged to engage a flat face 152 on the arm to hold the arm in the position shown in dotted lines in Fig. 7, and to engage a flat face 154 on the arm to hold the arm in the position shown in full lines in said figure. To hold the end of the thread in starting 60 the winding of a bobbin, the end of the thread may be inserted between the clamp- 65

ing member 118 and the flange on the bobbin, and clamped between said member and the bobbin when the bobbin is clamped on the winding shaft.

With the first part of the thread wound 70 on the bobbin in one direction and the remainder of the thread wound in the opposite direction, in unwinding the thread the inner end of the thread or the end of the part of the thread wound in the first direction is liable to be picked up by the unwinding thread before the reversal in the direction of the winding is reached, and a part or all of the thread wound in the first direction 75 will then be unwound from the bobbin prematurely. To prevent this difficulty the inner end of the thread is wound in or covered by several coils of thread wound in the first direction at the beginning of the 80 winding of the thread on the bobbin. This result is produced by holding the thread leading from the supply to the bobbin so that it is delivered to the bobbin close to one of the end flanges on the bobbin during 85 the winding of several coils on the bobbin at the beginning of the winding operation. The machine illustrated in the drawing is provided with a thread guide lever 156 pivoted at 158 on the frame and formed with 90 diverging projections 160 and 162, the recess between which forms a guide for the thread. The movement of the thread guide lever about its pivot in one direction is limited 95 by the engagement of the rear end of the lever with a stop pin 164 and the lever is acted upon by a coiled spring 166 which tends to maintain the lever in engagement 100 with the stop pin. The position of the thread guide lever when engaged with the stop pin 164 is such that the thread, as it passes through the thread guiding recess 105 between the projections 160 and 162, is held close to the left-hand flange of the bobbin. The thread guide lever is held in engagement 110 with the stop pin during the winding of several turns or coils of thread on the bobbin at the beginning of the winding operation, so that the end of the thread will be covered by several coils of thread wound 115 in the first direction. After the end of the thread is covered by a number of coils the thread guide lever is actuated to swing the forward end thereof to the right toward the right-hand flange on the bobbin so that 120 the thread is delivered to the bobbin nearer the central portion thereof. To this end the rear end of the thread guide lever is arranged to be engaged by the left-hand end of the shaft 78 as said shaft is moved longitudinally to the left during the winding 125 of the first part of a bobbin. At the start of the winding of a bobbin when the shaft is located in its limiting position toward the right, the position of the thread guide lever which is then held in engage- 130

ment with the stop pin 164 by the spring 166 is such that the rear end of the lever is located at some distance from the end of the shaft 78. Thus the thread as it is delivered to the bobbin is held by the thread guide lever close to the left-hand flange of the bobbin during the winding of several coils of thread on the bobbin. After the winding shaft has executed a number of revolutions, the end of the shaft 78 engages the rear end of the thread guide lever, and by the continued longitudinal movement of the shaft to the left, the thread guide lever is swung gradually in a direction to carry the forward end of the lever to the right, or toward the right-hand flange on the bobbin. As the shaft 78, following the reversal in the direction of rotation of the winding shaft, moves longitudinally to the right, the thread guide lever under the action of the coiled spring 166 will swing back toward its original or starting position.

Figs. 11 to 16 inclusive illustrate the manner in which the thread is wound on the bobbin, the length of thread wound in the first direction on the bobbin being indicated at T in said figures, and the remainder of the thread to that wound in the second direction, at T'.

Figs. 11 and 12 of the drawings illustrate the manner in which the winding of a bobbin is started with the thread held close to the left-hand flange of the bobbin by the thread guide lever. As shown in these figures, the thread at the beginning of the second turn or coil is laid across the end of the thread. It will not always happen that the end of the thread will be wound in by the second coil in this manner, but several coils may be wound on the bobbin before the thread end is covered. Figs. 13 and 14 illustrate the bobbin just after the direction of the winding of the thread on the bobbin is reversed, and shows the manner in which the thread is wound close to the left-hand flange of the bobbin during the first part of the winding operation. Figs. 15 and 16 illustrate a completely wound bobbin, and show the length of thread wound in the first direction on the bobbin covered by the thread wound in the second direction so that the latter thread is unwound first from the bobbin. It is to be noted that the manner in which the inner end of the thread is wound in or covered by one or more coils of the thread wound in the first direction, will prevent the bobbin thread from being threaded in the sewing machine in which the bobbin is used so that the thread wound in the first direction is drawn first from the bobbin.

Although the present invention was particularly designed to be embodied in machines for winding sewing machine bobbins, certain features of the invention may be

applied with advantage to machines for winding other forms of bobbins or thread carrier, and it is to be understood that the invention is limited only to the class of machines defined in the claims, and that it may be embodied in any form fairly within the scope of the claims.

Having explained the nature and object of the invention, and having specifically described a machine embodying the various features therein in their preferred forms, what is claimed is:

1. A bobbin winding machine having in combination, a winding shaft, driving connections for driving the shaft in reverse directions, a registering mechanism for registering the revolutions of the winding shaft during the first part of the winding operation, and means controlled by the registering mechanism for shifting the driving connections to cause a comparatively short predetermined length of thread to be wound on the bobbin in one direction and the remainder of the thread to be wound on the bobbin in the opposite direction. 90

2. A bobbin winding machine, having, in combination, a winding shaft, driving connections for driving the shaft in reverse directions, mechanism for actuating and controlling the driving connections to drive the shaft in one direction during the winding of a relatively small number of turns of thread on the bobbin and to drive the shaft in the opposite direction during the winding of the remainder of the thread on the bobbin, comprising a timing mechanism actuated in definite relation to the winding shaft, and means controlled from the timing mechanism for shifting the driving connections to reverse the direction of rotation of the winding shaft at a predetermined point in the winding operation. 105

3. A bobbin winding machine, having, in combination, a winding shaft, driving connections for driving the winding shaft in reverse directions, a latch for maintaining the driving connections in condition to drive the shaft in one direction, mechanism for automatically throwing out the latch after a comparatively short length of thread has been wound on the bobbin, and means for shifting the driving connections upon the release of the latch and for holding them shifted to drive the shaft in the reverse direction until the remainder of the thread has been wound on the bobbin. 115

4. A bobbin winding machine, having, in combination, a winding shaft, driving connections for driving the shaft in reverse directions, a latch for maintaining the driving connections in condition to drive the shaft in one direction, means for automatically releasing the latch, means for shifting the driving connections upon the release of the latch to drive the shaft in the reverse di- 125

rection, and means for shifting the driving connections to disconnect the same from the shaft.

5. A bobbin winding machine, having, in combination, a winding shaft, driving connections for driving the shaft in reverse directions, a latch for maintaining the driving connections out of operative relation to the shaft and for maintaining said connections in condition to drive the shaft in one direction, means for actuating the driving connections to connect the same with the shaft to drive the shaft in one direction upon the first release of the latch, the latch then operating to maintain the driving connections in operative relation to the shaft, means for automatically producing a second release of the latch, mechanism for shifting the driving connections upon the second release of the latch to drive the shaft in the reverse direction, and means for shifting the driving connections to disconnect the same from the shaft.

6. A bobbin winding machine, having, in combination, a winding shaft, driving connections for driving the shaft in reverse directions, a registering mechanism for registering the revolutions of the winding shaft during the first part of the winding operation comprising a second shaft, a nut in which said shaft is threaded, means for relatively turning the second shaft and the nut in definite relation to the winding shaft, and means controlled by the relative longitudinal movement of the second shaft and the nut in one direction only for shifting the driving connections to reverse the direction of rotation of the winding shaft.

7. A bobbin winding machine, having, in combination, a winding shaft, driving connections for driving the shaft in reverse directions, a latch for holding the driving connections out of operative relation to the winding shaft and for holding the driving connections in condition to drive the shaft in one direction, and means for controlling the latch.

8. A bobbin winding machine, having, in combination, a winding shaft, driving connections for driving the shaft in reverse directions, a latch for holding the driving connections out of operative relation to the winding shaft and for holding the driving connections in condition to drive the shaft in one direction, manually-controlled means for throwing out the latch to start the machine, and automatically-acting means to throw out the latch to cause the shifting of the driving connections to reverse the direction of rotation of the winding shaft.

9. A bobbin winding machine, having, in combination, a winding shaft, a thread guide, means for relatively holding the bobbin and thread guide stationary in position to guide the thread close to one flange of the

bobbin during the winding of one or more coils on the bobbin at the beginning of the winding operation, and means for relatively shifting the thread guide and bobbin.

10. A bobbin winding machine, having, in combination, a winding shaft, driving connections for driving the shaft in reverse directions, means for actuating and controlling the driving connections during the winding operation to drive the winding shaft in one direction during the winding of a portion of the thread on the bobbin and to drive the shaft in the reverse direction during the winding of the remainder of the thread on the bobbin, a thread guide, and means for relatively holding the bobbin and thread guide in position to guide the thread close to one flange of the bobbin during the winding of one or more coils on the bobbin at the beginning of the winding operation and for relatively shifting the thread guide and bobbin.

11. A bobbin winding machine having, in combination, a winding shaft, driving connections for driving the winding shaft in reverse directions, and means acting automatically during the winding operation to shift the driving connections to cause a comparatively short predetermined length of thread to be wound on the bobbin in one direction at the beginning of the winding operation and the remainder of the thread to be wound on the bobbin in the opposite direction.

12. A bobbin winding machine having, in combination, a winding shaft, driving connections for driving the winding shaft in reverse directions, means acting automatically during the winding operation to shift the driving connections to cause a comparatively short predetermined length of thread to be wound on the bobbin in one direction at the beginning of the winding operation and the remainder of the thread to be wound on the bobbin in the opposite direction, and means for varying the time in the winding operation at which said shift occurs.

13. A bobbin winding machine having, in combination, a winding shaft, driving connections for driving the winding shaft in reverse directions, and means acting automatically during the winding operation to shift the driving connections to cause a comparatively short predetermined length of thread to be wound on the bobbin in one direction at the beginning of the winding operation and the remainder of the thread to be wound on the bobbin in the opposite direction, said means comprising a timing mechanism operatively actuated during the rotation of the winding shaft in one direction and reset during the rotation of the winding shaft in the opposite direction.

14. A bobbin winding machine having, in combination, a winding shaft, and means

for actuating said shaft acting automatically to wind a comparatively short predetermined length of thread on the bobbin in one direction at the beginning of the winding operation and the remainder of the thread on the bobbin in the opposite direction.

15. A bobbin winding machine having, in combination, a winding shaft, driving connections for driving the winding shaft in reverse directions, and means acting automatically to throw out the connections for driving the shaft in one direction when a

comparatively short predetermined length of thread has been wound on the bobbin at the beginning of the winding operation.

15

16. A bobbin winding machine having, in combination, a winding shaft, means for clamping a flanged sewing machine bobbin thereon, and means for rotating the shaft to wind a comparatively short predetermined length of thread on the bobbin in one direction and the remainder of the thread on the bobbin in the opposite direction.

LAURENCE E. TOPHAM.
